(57) **CLAIM**

The ornamental design for a cranial orthotic, as shown and described.

DESCRIPTION

FIG. 1 is a perspective view of a cranial orthotic. FIG. 2 is a front view of the cranial orthotic of FIG. 7. FIG. 3 is a right side view of the cranial orthotic of FIG. 7, the left side view being a mirror image of the right side view. FIG. 4 is a rear view of the cranial orthotic of FIG. 7. FIG. 5 is a top view of the cranial orthotic of FIG. 7. FIG. 6 is another perspective view of the cranial orthotic of FIG. 7. FIG. 7 is a bottom view of the cranial orthotic of FIG. 7. FIG. 8 is a side perspective view of the cranial orthotic in a disconnected configuration. FIG. 9 is a right side view of the cranial orthotic in a disconnected configuration, the left side view being a mirror image of the right side view; and, FIG. 10 is a top view of the cranial orthotic in a disconnected configuration. The broken lines in the drawings denote structure that is not part of the claimed design.
